UNITED STATES PATENT OFFICE.

ROBERT S. BOYLE, OF FORT BRANCH, AND WALTER G. CLEVELAND, OF CYNTHIANA, INDIANA.

BALL-BEARING ELECTRIC TROLLEY-WHEEL.

No. 821,400.

Specification of Letters Patent.

Patented May 22, 1906.

Application filed June 16, 1904. Serial No. 212,863.

To all whom it may concern:

Be it known that we, ROBERT S. BOYLE, a resident of Fort Branch, county of Gibson, and WALTER G. CLEVELAND, a resident of Cynthiana, county of Posey, State of Indiana, citizens of the United States, have invented certain new and useful Improvements in Ball-Bearing Electric Trolley-Wheels, of which the following is a specification.

10 This invention relates to ball-bearing electric trolley-wheels.

The object of our invention is the provision of a light, simple, and comparatively inexpensive ball-bearing electric trolley-wheel having improved means for journaling the trolley-wheel and novel provision for the removal of the trolley-wheel and its bearings, whereby assembly or separation of the parts may be quickly and easily accomplished.

20 The invention also contemplates the provision of an improved ball-bearing for a trolley-wheel and a novel construction of the trolley head or harp whereby durability, strength, and securing of the parts is had with slight possibility of derangement to afford means for quick and easy repair when necessary.

The detailed embodiment of the invention which at this present time is the best we have 30 conceived is set forth fully hereinafter, and the novel features of the invention are recited in the appended claims.

In the accompanying drawings, Figure 1 is a side elevation; Fig. 2, a front elevation; 35 Fig. 3, a front elevation with the hinged part of the harp thrown back; Fig. 4, a side elevation with the hinged part of the harp thrown back and the trolley-wheel removed; Fig. 5, a section on line 4-4 of Fig. 1; Fig. 6, a section 40 on line 6-6 of Fig. 2, and Fig. 7 a detail of one of the ball-bearings.

The harp or trolley head 1 is of metal and provided with a socket 2 to receive the trolley-pole 3 and fasten thereto in any preferred manner. The harp is formed in two 45 duplicate parts considered longitudinally and transversely thereof, one of the parts 4 being rigid with the socket 2 and the other part 5 being suitably hinged to the part 4 at 6. A 50 screw 7 or other suitable fastening secures the hinged part 5 to the stationary part 4 of the harp. As will be observed, the two parts 4 and 5 are of substantially U shape viewed in front elevation, and in each arm of

the part 4 and in each arm of the part 5 are provided triangular boxes 8, which when the parts 4 and 5 are together constitute hollow square boxes provided with the aligned circular apertures 9 and 10, on opposite sides thereof, the inner aperture 10 being formed with a surrounding flange 11, which prevents the trolley-wheel from striking the harp.

The ball-bearings consist of square plates 12 and 13, secured together at their corners by rivets or fastenings 14 and provided with a ball-race formed by the annular grooved parts 15 and 16. Within and extending through the plates 12 and 13 is a hollow or tubular cone 17, having a peripheral ball-race 18. Balls 19 run in this ball-race 18 and in the ball-race formed by the annular grooved parts 15 and 16. The respective plates 12 and 13 are received and fit in the boxes 8, and the width of the annular 75 grooved parts 15 and 16 is such that the fit is a snug one, so that the ball-bearings are secured firmly in position when the parts 4 and 5 of the harp are secured together by the screw 7, which leaves the ends of the tubular 80 cone 17 projecting slightly beyond the faces of the harp, and said cones are free to turn with the greatest ease. The trolley-wheel 20 has its shaft or spindle 21 integral therewith and received snugly and tightly in the 85 cones 17, so that as said trolley-wheel rotates the cones turn with it and the balls constitute the bearing for said trolley-wheel.

It will be seen that by simply throwing back the hinged part 5 of the harp the bearings and trolley-wheel can be taken out and separated for replacement by new bearings or a new trolley-wheel or for the institution of any other repairs, and these operations can be carried on quickly and easily.

We have shown the plates 12 and 13 and the cones 17 as formed of sheet metal with struck-up ball-races; but it is obvious that the ball-races could be cast or cut out from solid metal and that other changes of construction could be resorted to in forming the harp, and the shaft of the trolley-wheel could be secured to said wheel instead of being formed integral therewith. We do not, therefore, limit ourselves to the specific construction herein shown and described, but lay claim to all modifications falling within the spirit and scope of the invention.

Having thus described our invention, what we claim as new, and desire to secure by Letters Patent, is—

1. In a trolley, the combination with a trolley wheel and axle, of a trolley head or harp comprising sections adapted for opening in relation to each other in a general transverse direction to the trolley-wheel axle, and removable ball-bearings for the axle which are held in position by the sections of the harp when closed. 5
2. In a trolley, the combination with a trolley harp or head comprising sections adapted to open and close in relation to each other and having means for holding bearings when closed, of bearings removably held by said harp-sections when closed, and a trolley-wheel journaled in said bearings. 15
3. In a trolley, the combination with a trolley harp or head comprising separable sections adapted to open and close in relation to each other and having means for holding bearings when closed, of self-contained ball-bearings removably held by said harp-sections when closed, and a trolley-wheel journaled in said bearings. 20
4. In a trolley, the combination with a trolley harp or head comprising sections adapted to open and close in relation to each other and having boxes adapted to hold bearings when the sections are closed, of self-contained bearings received in said boxes and held there when the harp-sections are closed, and a trolley-wheel journaled in said bearings. 25
5. In a trolley, the combination with a trolley harp or head comprising sections adapted to open and close in relation to each other and having boxes adapted to hold bearings when the sections are closed, of self-contained ball-bearings received in said boxes and held there when the harp-sections are closed, and a trolley-wheel journaled in said bearings. 35
6. In a trolley, a harp or head composed of relatively movable substantially U-shaped sections adapted to close together, said sections having boxes, self-contained removable bearings in said boxes, and a trolley-wheel journaled in said bearings. 45
7. In a trolley, a harp or head composed of relatively movable substantially U-shaped sections adapted to close together, said sec- 50
- tions having boxes, self-contained removable ball-bearings in said boxes, and a trolley-wheel journaled in said ball-bearings. 55
8. In a trolley, the combination with a harp or head, of ball-bearings held by the arms of said harp or head and comprising plates having grooves which together form a ball-race, fastenings directly securing the plates together, a cone having a ball-race, balls in said ball-races, and a trolley-wheel supported by said cones. 60
9. In a trolley, the combination with a harp or head comprising substantially U-shaped relatively movable sections having matching polygonal boxes, of exteriorly-polygonal bearings removably received in said boxes, and a trolley-wheel supported by said bearings. 65
10. In a trolley, the combination with a harp or head comprising relatively movable sections having matching boxes, of bearings removably received in said boxes and held therein by the sections when closed, and a trolley-wheel supported by said bearings. 70
11. In a trolley, the combination with a harp or head comprising hinged sections having matching polygonal boxes, of exteriorly-polygonal bearings removably received in said boxes, and a trolley-wheel supported by said bearings. 75
12. A trolley-harp comprising a fixed bifurcated arm provided with bearings, a bifurcated upper arm hinged to the fixed arm, and a trolley-wheel lying between the branches of the arms and having integral trunnions engaging the bearings. 80
13. A trolley-harp comprising a fixed bifurcated arm provided with bearings, a trolley-wheel having integral trunnions which engage the bearings, a hinged bifurcated upper arm engaging the trunnions and means for locking the upper arm so that the wheel cannot be thrown from its bearings. 85

In testimony whereof we have signed our names to this specification in the presence of two subscribing witnesses.
